UNITED STATES PATENT OFFICE.

WILLIAM E. FARLEY, OF EL RENO, OKLAHOMA.

LUBRICATOR.

Application filed August 28, 1922. Serial No. 584,797.

To all whom it may concern:

Be it known that I, WILLIAM E. FARLEY, a citizen of the United States, residing at El Reno, in the county of Canadian and State 5 of Oklahoma, have invented certain new and useful Improvements in Lubricators, of which the following is a specification, reference being had to the accompanying drawings.

10 This invention relates to improvements in lubricators, and more particularly to a device for lubricating steam engines.

An important object of the invention is to provide a lubricator adapted for the feeding 15 of hard grease to the valves of a steam engine.

A further object of the invention is to provide a device of this character which is automatic in its operation and in which the 20 lubricating action is continually taking place during running of the engine.

A still further object of the invention is to provide a device of this character which is extremely simple and rugged in construction 25 and which may be readily applied to the engine with which it is employed, thus providing a device admirably adapted for use upon locomotive engines and the compressor engines of locomotives.

30 These and other objects I attain by the construction and arrangement shown in the accompanying drawings wherein for the purpose of illustration is shown a preferred embodiment of my invention and wherein like reference characters designate like parts throughout.

In the drawings:—

Figure 1 is a sectional view showing a lubricator constructed in accordance with my 40 invention and embodying a feed device for use with saturated steam;

Figure 2 is an enlarged section on the line 2—2 of Figure 1;

Figure 3 is a similar section on the line 45 3—3 of Figure 1;

Figure 4 is a longitudinal sectional view taken through a lubricator showing a feed device for use with superheated steam;

Figure 5 is a transverse sectional view 50 taken on the line 5—5 of Figure 4; and

Figure 6 is an enlarged sectional view of

the upper end of the super-heated steam feed control.

Referring now more particularly to the drawings, the numeral 10 indicates the main casing having a top 11 provided centrally with a filling opening closed by a cap 12, and a bottom 13 having a central bore 14 formed therein, the purpose of which will presently appear. The lower end of the casing is 60 adapted for engagement in a steam chest or steam feed pipe leading to the engine and in the present instance is shown as provided with a depending threaded skirt 15 adapted to be engaged by a reducer cap 16 which at 65 its lower end engages in the steam chest 17 or in the steam feed pipe, the latter construction not being herein illustrated.

Having its lower end mounted in the threaded opening 14 of the bottom 13 of the 70 casing 10 is a feed regulator 18, the construction of which is varied to suit the needs of the engine and the type of steam employed in operating the engine. In the form shown in Figures 4 to 6, the feed regulator construction employed is one particularly adapted 75 for use in connection with locomotive engines employing super-heated steam. In this form a threaded tube 19 has its lower end engaged in the opening 14 and its upper end 80 embracing a downwardly extending portion formed in the base of a secondary container 20. This downwardly extending portion of the base is provided with a bore 21 in which is mounted a control element 22. This control element consists in a tubular member, the bore of which is reduced, as indicated at 85 23, at spaced intervals, the reduction being abrupt forming shoulders, the purpose of which will presently appear. Adjacent its 90 upper end the bore is provided with a considerable enlargement 24 and beyond this point, at the upper extremity of the control member 22, the bore is reduced to a small orifice 25. The upper end of the control member 22 extends above the upper end of the auxiliary container 20 and is received within the bore 26 of a threaded cap 27 forming the upper end of the container.

This cap is provided with an aperture 28, 100 the walls of which slant downwardly and this aperture communicates with the bore

26 of the cap. This bore is of such size that a space is left between the adjacent faces of the walls of the bore and the upper face of the control member 22.

5 This construction, as hereinbefore stated, is particularly adapted for use at the steam chests of large engines, such as locomotive engines, employing super-heated steam. As is well known to those familiar with the 10 art, the shifting of the valve 29 of these engines divides the movement of the steam through the steam chest into periods in which there is no movement and feed periods during which the steam is passing rapidly into the cylinders 30. In the operation of this form of device, during those periods when no steam is passing through the steam chest into the cylinders, the back pressure of the steam causes steam to pass upwardly 15 through the restricted bore of the control member 22 and act upon the hard grease within the container 10 to reduce the same to liquid and this liquid will flow into the auxiliary container 20 until the same is full. 20 During those periods when steam is passing to the cylinders the passage of the steam through the chest will create a suction through the control member 22 relieving the pressure within the container 10 and permitting the liquefied grease to pass downwardly through the bore of the control member, and in fact tending to draw the same therethrough at a fairly rapid rate. It will, 25 of course, be understood that these operations take place very rapidly and that the contents of the chamber 10 will be alternately placed under high pressure and heat and under suction to form at all times a liquefied grease which may flow through the 30 bore of the control member and into the steam chest. The shoulders 23 and the pocket or enlargement 24 of the control member serve to prevent the passage of the steam upwardly through the control member from 35 forcing all of the liquefied grease back into the container 10. It will, of course, be understood that condensation water forming within the container 10 will raise the level 40 of the hard grease so as to maintain the grease always in position for engagement by the hot steam injected through the control member. In this form it will be noted that the container 20 has its main portion or body disposed below the intake end of the 45 control member 22, the purpose of this construction being to prevent the collection of a large amount of the liquefied grease at the orifice and accordingly to prevent too large a quantity of this liquefied grease being drawn into the valves of the engine during 50 the feed period.

In the construction shown in Figures 1 to 3, the control member consists of an attaching element 31 having its lower end threaded for engagement in the opening 14

and its upper end externally threaded for engagement with a reducing element 32. Seated upon the upper end of the attaching member 31 is a shoulder 33 formed on a control element 34 corresponding to the control 70 element 22 hereinbefore described. This control element has its lower end extending downwardly into the attaching member 31 and is of such a size that it is spaced from the walls thereof for a purpose 75 hereinafter to appear. The upper end of the control member 34 above the shoulder 33 is externally screw threaded, as at 35, for engagement in the threaded orifice formed in the lower end of an auxiliary chamber 36. 80 The bore of the control member 34 is restricted, as in the case of the control member 22, but in the construction at present illustrated but a single constriction 37 located at the upper extremity of the bore is employed. The exterior of the lower end of the auxiliary chamber 36 is screw threaded for engagement with the reducer 32 and by tightening this reducer, the container may be forced downwardly to seat the shoulder 33 85 firmly against the upper end of the attaching member 31. The upper end of the auxiliary container is closed by a removable cap 38 having an orifice 39 aligned with the bore of the control member 34 and enlarged 90 at its lower end, as indicated at 40.

It will be noted that in this construction of feed regulator which is interchangeable with the feed regulator hereinbefore described, the upper end of the control element forms the lower end of the auxiliary chamber and that accordingly approximately all of the liquefied grease entering the chamber is positioned to be withdrawn from the chamber during the steam feeding period. This is due to the fact that this construction just described is particularly adapted for use in conjunction with engines employing saturated steam which is of low heating value and which will not accordingly reduce the grease rapidly enough to cause the surplusage of liquefied grease to be withdrawn for lubricating purposes. For the same reason the control member 34 is shown of a size providing a space between its exterior surface and the inner face of the wall of the attaching member 31, this allowing the steam to surround the control member and maintain the heat of the same at a point preventing solidifying of the grease. 115

Particular attention is directed to the construction of the chamber 20 employed with lubricators for engines employing super-heated steam, since the arrangement disclosed is vitally necessary to the proper operation of the lubricator. In tests of the lubricator in which a chamber of the type shown in Figures 1 to 3 was employed, there was found that too great amounts of the grease was fed to the cylinders and that 125 130

accordingly over-lubrication with its general injurious results occurred and it became necessary to materially reduce the size of the orifice 25 employed for controlling the 5 passage of the fluid and the entrance of steam. With this reduction of the orifice it becomes necessary to more highly heat the fluid in order that it may readily pass through the orifice to the cylinders. By the 10 construction shown the entrance of steam causes liquefaction of the hard grease within the chamber 10 and this liquefied grease passes into the interior of the chamber 20 where it becomes extremely highly heated 15 and forced from the chamber 20 into the chamber 10 to be replaced by cooler grease which is in turn heated and returned to the chamber 10, resulting during the operation of the engine in liquefaction of all of the 20 grease contained in the chamber 10 and a constant circulation thereof so that the steam, grease and condensation water from the steam are intermixed in the chamber. During its passage over the orifice 25, a 25 small percentage of the passing grease passes downwardly through the orifice for the lubrication of the engine.

Each of the forms hereinbefore described have been employed in actual operation 30 upon a locomotive, the first form being employed for lubricating the valves of the engine cylinders proper and the second form being employed for lubricating the air compressor engine, which it is well known is 35 operated by saturated steam. In such usage it has been found that the lubrication of the engine is much more efficient than where ordinary lubrication is employed, tests demonstrating a saving of from one-half to one 40 ton of coal in an engine operating over a one hundred and fourteen mile division in heavy freight service. It will be obvious 45 that the simple construction of the lubricator and the fact that it employs a principle whereby it operates only during the operation 50 of the engine and automatically comes into operation without the necessity of control by the fireman or engineer of the engine, renders the same extremely desirable 55 for use in conjunction with locomotive engines. It will furthermore be obvious that the constructions hereinbefore set forth are capable of some change and modification 60 without materially departing from the spirit of my invention and I accordingly do not limit myself to such specific structure except as hereinafter claimed.

I claim:

1. In a lubricator, a main container for 65 the reception of a hard lubricant, a secondary container arranged within the main container, a control element having a bore communicating at one end with the secondary container and at the opposite end with an intermittently flowing source of steam, and

a port in said secondary container providing communication between the main container and secondary container and aligned with the bore of said control element.

2. In a lubricator, a main container for 70 the reception of a hard lubricant, a secondary container arranged within the main container, a control element having a bore communicating at one end with the secondary container and at the opposite end with an intermittently flowing source of steam, and a port in said secondary container providing communication between the main container and secondary container and aligned with the bore of said control element, 75 the bore of said control element being enlarged at the point spaced from the end thereof communicating with said secondary container.

3. In a lubricator, a main container adapted 80 for the reception of a hard lubricant and provided with a filling opening through which the lubricant may be inserted, a secondary container arranged within the main container and comprising a hollow body portion provided in its lower end with an 85 opening and having an open upper end, a cap closing such open upper end and having a port formed therein, the lower end of the port being enlarged and a control element extending into the opening of the lower end of the secondary container and having a bore aligned with the port of said cap.

4. In a lubricator, a main container adapted 90 for the reception of a hard lubricant and provided with a filling opening through which the lubricant may be inserted, a secondary container arranged within the main container and comprising a hollow body portion provided in its lower end with an 95 opening and having an open upper end, a cap closing such open upper end and having a port formed therein, the lower end of the port being enlarged, and a control element extending into the opening of the lower end of the secondary container and having a bore aligned with the port of said cap, 100 said control element extending into the enlarged lower end of said bore.

5. In a lubricator, a main compartment 105 comprising a grease container, a chamber arranged within the grease container, a feed control port extending into the chamber and communicating with the steam supply of the engine to be lubricated, and a passage 110 connecting the grease container and the chamber arranged to provide circulation of grease passing into and out of the container from and to said main container over the feed port.

6. In a lubricator, a main compartment 115 comprising a grease container, a chamber arranged within the grease container, a feed control port extending into the chamber and communicating with the steam supply of 120

130

the engine to be lubricated, and a passage connecting the grease chamber and the secondary container arranged to provide circulation of grease passing into and out of the secondary container from and to said main container over the feed port, the bore of said feed port being in the form of a minute opening over which the grease passes, said bore being increased in diameter at spaced intervals toward the point of connection with the steam supply of the engine.

In testimony whereof I hereunto affix my signature.

WILLIAM E. FARLEY.
